UNITED STATES PATENT OFFICE.

GERD A. NULL, OF CRAIG, IOWA.

SAFETY-LOCK.

1,109,081.

Patented Sept. 1, 1914.

Application filed February 4, 1914. Serial No. 816,581.

To all whom it may concern:

Be it known that I, GERD A. NULL, a citizen of the United States, residing at Craig, in the county of Plymouth and State of Iowa, have invented certain new and useful improvements in Safety-Locks, of which the following is a specification, reference being had to the accompanying drawings.

This invention relates to new and useful improvements in safety locks and more particularly to a safety lock for a wagon dump in grain elevators, the object of the invention being to provide a lock which will be rendered effective when the trap door of the grain pit is closed so that the dump logs will not drop down when a team is driven on the dump.

Another object of the invention is the provision of a safety lock of the above character which will possess advantages in points of efficiency and durability, is inexpensive to manufacture and, at the same time, is simple in construction and operation.

With the above and other objects in view, the invention consists in the novel features of construction and the combination and arrangement of parts hereinafter more fully described, pointed out in the claim and shown in the accompanying drawings, in which,

Figure 1 is a detail perspective view of a locking device constructed in accordance with my invention; Fig. 2 is a side elevation illustrating the application of my device.

Referring more particularly to the drawings, 1 indicates the frame of the dump and 2 the logs thereof, said logs being provided in their ends with the longitudinal openings 3. Suitable wear plates 4 are secured to the ends of the logs 2 and are provided with a central opening adapted to be arranged in alinement with the openings 3. Disposed beneath the dump and rotatably mounted within the lower ends of the hangers 5, is the main shaft 6, said hangers being secured in any suitable manner to the underside of the dump. Secured to each end of the shaft 6 and adapted to be actuated thereby, are the shifting arms 7, said arms being provided at their inner ends with the sleeves 8, having set screws 9 adapted to engage the ends of the shaft 6, so that the arms 7 will rotate therewith. Suitable supporting brackets 10 are provided, the ends

of which are secured to the frame 1, in any suitable manner. The brackets 10 are provided at their medial portions with sleeves 11 which form guides for the movable locking pins 12, the ends of which are pointed, as shown at 13 and are adapted to be inserted within the openings 3 in the ends of the logs 2 to prevent the same from dropping down. The locking pins 12 are provided at their outer ends with the loops 14 which are adapted to receive the upper ends of the shifting levers 7, the rotation of the shaft 6 actuating said levers and reciprocating said pins to lock or unlock the logs 2. Stop pins 15 are carried by the locking pins 12 and are adapted to engage the sleeves 11 to limit the sliding movement of the pins 12. It will be apparent that the plates 4 will eliminate the wear of the pins 12 upon their sliding movement in the openings 3.

The shaft 6 is rotated by the opening and closing of the trap door 16 through the medium of the bar 17, said bar being provided at its upper end with a flanged casting 18, whereby the bar may be readily secured to the door 16, by the use of screws or similar fastening means. The bar 17 is provided with a longitudinal slot 19 which is adapted to receive the transverse pin 20 carried by the outer ends of the arms 21, said arm being provided at its inner end with a sleeve 22 carrying a set screw 23 adapted to engage the shaft 6, so that the actuation of said arm will rotate the shaft 6. The arm 21 will be actuated to rotate the shaft 6 when the pin 20 reaches the ends of the slot 19, upon the movement of the bar 17, said bar being moved by the opening and closing of the door 16.

From the above description, taken in connection with the accompanying drawings, it will be readily apparent that I have provided a simple and durable safety lock for wagon dumps in grain elevators. In opening the trap door 16, which leads to the grain pit, the bar 17 will be actuated to rotate the shaft 6 through the arm 21 and reciprocate the pins 12 by means of the levers 7, thus withdrawing the pins 12 from the openings 3 in the ends of the logs 2. On the other hand, the locking pins 12 will be inserted within the openings 3 upon closing the door 16, thus preventing the logs from

dropping down when a team is driven on the dump.

It will be apparent that my improved safety lock is extremely simple in construction, may be manufactured at a comparatively small cost and readily applied to use in connection with wagon dumps on grain elevators.

While I have shown and described the preferred form of my invention, it will be obvious that various changes in the details of construction and in the proportions may be resorted to for successfully carrying my invention into practice, without sacrificing any of the novel features of construction or departing from the scope of the appended claim.

Having thus described this invention, what I claim is:

A device of the class described including 20 movable locking pins, having loops formed at their outer ends, a rotatable shaft, levers carried thereby and having their outer ends movable in said loops, a movable bar having a slot, an arm carried by said shaft, and a pin carried by said arm and arranged within said slot, as and for the purpose set forth.

In testimony whereof I hereunto affix my signature in the presence of two witnesses.

GERD A. NULL.
